UNITED STATES PATENT OFFICE

2,230,003

COMBINATION RECORDER AND PHONO-
GRAPH APPARATUSDonald H. Mitchell, Chicago, Ill., assignor to
Galvin Manufacturing Corporation, Chicago,
Ill., a corporation of Illinois

Application May 15, 1940, Serial No. 335,369

3 Claims. (Cl. 274—39)

My invention is directed to a combination recorder and phonograph apparatus which is adapted for use alone, or in combination with a radio receiver.

5 In prior apparatus adapted to record sound transmitted from any source through a microphone or the like, or duplicate a record, it has been necessary to provide two turntables. The two turntables are employed only when it is desired to duplicate a record, when the blank is mounted on one turntable and the record on the other. However, in order to provide for all 10 types of recording with a particular apparatus, and hence the maximum flexibility for the machine, two turntables were required. This resulted in bulky and expensive apparatus, both as to the mechanism itself, and the cabinet housing the same. The high price limited the volume of sales, and the large cabinet was objectionable, because often appropriate space is not 15 available in a home. Disadvantages were found in the operating mechanism itself, such as the difficulty in maintaining the two turntables in synchronization during rotation. The art has attempted to solve this problem by two synchronous motors, one on each turntable. This not only is expensive and adds to the bulk, but also, the motors sometimes get out of synchronization 20 with consequent harm to the recording. Another problem in the prior art is the elimination of so-called table rumble due to vibration, or any mechanical movement, other than mere rotation in the turntables, which is reproduced in the recording.

35 It is an object of my invention to provide improved and simplified recorder and phonograph apparatus.

A further object of my invention is to provide 40 an inexpensive and compact recorder and phonograph device.

Another object of my invention is to provide recorder and phonograph apparatus adapted not only to make an original recording, but also to 45 duplicate in the apparatus a previously played record, and accomplish the latter with absolute synchronization between the rotation of the completed record, and the blank upon which the record is being duplicated.

50 A still further object of my invention is to provide apparatus of this character in which there is a minimum of rumble in the recording on the blank being cut.

One of the features of my invention is the provision of recorder and phonograph apparatus on

which records may be duplicated, but which apparatus requires only a single turntable.

Another feature of my invention is the provision of a removable pedestal or duplicator which rests upon the blank being cut for the recording, and supports the record from which the recording is being made, but which pedestal or duplicator is removable from the position on the blank so that the vertical height of the apparatus in non-operating condition may be reduced. A vertically adjustable pick-up arm is movable from a position above the record downwardly in the cabinet to a position upon the blank.

15 A still further feature of my invention is the provision of absolute synchronization between the record being duplicated and the blank upon which the recording is made, and the minimization of table rumble by virtue of a superimposed record and blank on the same turntable which act together to substantially cancel out such rumble.

20 Other objects, features, and advantages of my invention will be apparent from the following description taken with the drawing, in which:

25 Fig. 1 is an elevational view of the complete recorder and phonograph apparatus with a portion of the mechanism in vertical section to illustrate the details of the mechanism.

30 Fig. 2 is a perspective view of the duplicator of my invention on a reduced scale.

35 In practicing my invention I provide a rotatable turntable suitably supported in a housing and having an upwardly extending center spindle. The turntable supports in the usual position either a record or a blank for recording and a pedestal or duplicator is positioned on the blank and centered at the spindle. The pedestal includes a bottom and a top plate secured to, and spaced apart by, a hollow post having a spring-pressed clamp retained on the post, and a spindle-like extension on the post for centering a blank to be recorded on the top plate of the pedestal, and also for centering the clamp with reference thereto.

40 A suitable recording arm is mounted on the housing for cutting the sound grooves in the blank, and a second arm provided with a pick-up is supported on a rotatable elongated post mounted on the housing. The pick-up arm is vertically movable so that it may be lifted to a height suitable for playing the record being duplicated, and yet is retractable to a position adjacent the top of the housing when playing a record on the turntable, or upon removal or non-use of the duplicator. A suitable electrical 45

50

55

system for accomplishing playing and recording is provided in the housing.

Referring now to Figure 1, the housing 10 is provided with a top 11 from which a suitably mounted spindle 12 extends upwardly. A motor 13 is mounted below the top 11 and is suitably connected to a turntable 14 rotatably mounted upon the spindle 12.

As suggested above, in prior combination recorder and phonograph devices, only a single turntable is required if a recording is made from sound projected into a microphone, or the like. However, very often it is desired to duplicate either a record which has been made on the recorder device, or a record of any description purchased for playing. In order to duplicate a record it has been necessary to provide two turntables in the prior devices. The difficulties and high cost peculiar to this apparatus were discussed above. This problem is solved in the present invention by means of a pedestal, or duplicator unit 16 comprising a stamped-out bottom plate 17, a corresponding top plate 18, and a spacing and connecting post 19, rigidly connected to each plate. In the illustrated embodiment of the invention, the post is peened over adjacent the top and the bottom thereof to secure the plates and post together.

The post 19 is hollow throughout its length and includes an enlarged bore or chamber 21 at the bottom, and a more restricted bore 22 adjacent the top. The two bores are defined by an intermediate annular shoulder 23. In using the duplicator, it is merely placed upon a blank 24 adapted to be cut for a recording, and the latter is supported in the usual way upon the turntable 14 and centered at the spindle 12. The bottom plate 17 of the duplicator conforms in diameter substantially to the diameter of the central portion of the blank 24 upon which normally no recording is made. The duplicator is likewise centered on the spindle 12 with the latter extending into the bore 21, as shown in Fig. 1. Relative movement between the blank 24 and the duplicator is prevented by means of a spring-pressed pin 25 supported on the turntable 14 as shown in Fig. 1, and normally extending through corresponding holes in the turntable and the recording blank, and through a hole 26 in the plate 17 of the pedestal. Recording blanks are normally supplied with the necessary hole as described.

Any type of record may be duplicated on the blank 24. If a standard commercial record as 27 is being duplicated, it is supported by the top plate 18 of the duplicator, and is directly carried by a rubber friction disc 28 on the top surface of such plate. If a home recording, or the like, on the usual blank 30 is being duplicated, it is normally supported upon the standard record 27, because it does not have sufficient body to stand up alone and support a pick-up arm at a part extending beyond the circumference of the top plate 18. The record 27 or the member 30 is centered on the top plate by an integral extension 29 of the post 19. The outside circumference of the extension 29 corresponds to the circumference of the spindle 12, and hence readily fits into the standard center aperture of a record, or recorded blank. The record 27 alone, or the record 27 and recorded blank 30 are retained on the duplicator by means of a clamp unit which comprises a clamp 31 having a U-shaped body portion and a pair of downwardly extending rounded ears 32 at each end of the body portion. The clamp is pivotally secured to, and straddles the top of a

pin 33 carried in the bores 21 and 22 of the post and retained therein under tension by means of a spring 34. The spring rests against the shoulder 23 at the top, and against a washer 35 on the pin 33 at the bottom. The pivotal supporting portion 31 on the clamp 31 will extend into a cavity 36 in the extension 29 in the retracted position of pin 33.

As is evident from the full, and the dotted line illustration in Fig. 1, the record 27 or recorded blank 30, may be positioned on the pedestal and removed therefrom, by pulling the clamp 31 upwardly against the spring pressure 34, a distance sufficient to permit the clamp 31 to be pivoted on the pin 33 to a substantially upright position. In this position the ears 32 adjacent the post will rest against the top edge of the annular extension 29, and a record, or recorded blank will readily pass over the upright clamp at their center aperture and into a centered position on the rubber disc 28 for the top plate 18 of the duplicator. After positioning the record, the clamp 31 is pulled slightly upwardly, and pivoted back to a horizontal position, from which it may be lowered into the horizontal clamping position illustrated in full lines in Fig. 1.

The recording and the playing operations are carried out respectively by a suitable recording unit 42 mounted upon the housing 10 so that it may be pivoted both vertically and horizontally for the usual movements required for the recording operation, and a pick-up unit 43. A cutter 44 is secured in the unit 42 and rests on the surface of the blank 24 to cut grooves into such blank in accordance with the sounds transmitted through suitable electrical apparatus (not shown) from a microphone, or a pick-up unit. In order that a standard record, or a recorded blank may be played, either from the turntable 14 or from the top of the duplicator 16, my invention provides for a vertically adjustable pick-up unit 43. In one commercial embodiment of the invention this pick-up unit includes an arm 46 pivotally mounted on a bracket 47, which in turn is rigidly secured to an elongated post 48, and a needle 49 for riding in the usual manner in a record groove. Suitable electrical elements and circuits are likewise provided for the pick-up unit, but are not shown as they do not per se form a part of my invention. The post 48 is directly supported in a bushing 51 rigidly secured to the top plate 11 of the housing 10 by means of a suitable nut and washer combination as shown at 52 below the top plate 11. The bushing has a central bore 53 extending from top to bottom with an intermediate stop shoulder 54. The post 48 has an outwardly turned flange 56 at the bottom thereof which engages the stop shoulder 54 of the bushing to limit the upward movement of the post 48 and hence the entire unit 44.

In using the pick-up unit 44 on a record or recorded blank on the turntable 14, the lower arm of the bracket 47 rests upon the top face of the bushing 51. The post 48 extends over its length through the bushing 51 and into the housing 10. This is shown in dotted lines in Fig. 1. When playing a record or recorded blank on the pedestal or duplicator 16, the pick-up arm 46, or the bracket 47, may be grasped and the entire unit lifted upwardly until limited by the shoulder 54, and flange 56. In this position a spring-pressed ball, or detent 59, engages an annular groove 61 in the post 48, and holds the post and unit in extended position. Upon exerting a downward pressure on the post 48,

through the arm 46, or bracket 47, the ball 59 is forced against spring pressure out of engagement with the groove 61, and the unit 44 may be moved to the restricted position shown in 5 dotted lines.

In the present invention, therefore, I have provided a compact, inexpensive, and efficient apparatus for playing records and for recording records either in duplication of a record, or of sound 10 transmitted from any of the other usual sources. With the use of a removable pedestal or duplicator, and a vertically adjustable pick-up arm, it is possible to compress the overall vertical height of the operating mechanism so that a 15 closed cabinet for the apparatus in idle position is of a very convenient and compact size. In addition to the advantages in the use of my invention from the standpoint of bulk and expense, materially improved operating conditions are 20 provided, even in comparison to the prior more expensive and bulky equipment. The blank upon which the recording is being made, and the record being duplicated on the blank, both being rotatable on a single turntable, are maintained 25 in absolute synchronism and provide maximum recording quality from this standpoint. Furthermore, with the blank and record being superimposed on the single turntable, the very troublesome table rumble of the prior devices which 30 modulates the recording is minimized in my apparatus inasmuch as the vibrations of the turntable, or in fact any mechanical movement in the turntable, is substantially canceled out. A further operating advantage results from the fact 35 that the vertically movable pick-up arm in my invention can be almost instantaneously moved from the record being duplicated to the blank upon which the recording is being made for playing back any portion of the recording. This 40 can be done either during the progress of such recording or at the completion of the same. With the two-turntable apparatus some complication often arises in moving the pick-up arm from the playing turntable to the radially spaced recording turntable.

Although my invention has been illustrated and described in its preferred embodiment, it is understood that further modifications and alterations thereof may be made within the full intended scope of the invention as defined by the appended claims.

I claim:

1. A pedestal for removable mounting on a turntable for record playing apparatus, said pedestal including a bottom portion and a top portion, both of substantially equal diameters, and a combination spacing and connecting portion intermediate said top and bottom portions, with said combination portion having a bore extending entirely therethrough and open at one end

thereof, and an extension on said combination portion at the other end of said bore extending at right angles to and above the top portion, a clamp at said extension having a shank pivotally connected thereto and extending downwardly 5 into said bore, and a spring retained in said bore and operatively connected with said shank exerting a force thereon to pull said shank downwardly into said bore.

2. A record support for record recording and 10 playing apparatus adapted to be supported on a turntable at an upwardly extending spindle for said apparatus, said record support including a pair of vertically spaced plate members of substantially equal diameters, a hollow post rigidly secured to each of said members adjacent its ends and spacing said members apart, with one end of said post adapted to receive the turntable spindle, and the opposite end of said post having an internally cupped annular portion 15 projecting beyond the plate member at that end, and releasable clamping means for bearing downwardly on a record and retaining said record irrespective of the thickness thereof on said plate member at the projecting end portion, 20 said clamping means including a clamp extending crosswise of said projecting end portion in clamping position and of such size and shape so that it may be upended and extend into said internal cup of said projecting portion in non-clamping 25 position, a spring within said post operatively connected with said clamp and exerting a downward pull on said clamp.

3. In sound recording and reproducing apparatus having a single frame means, a phonograph record means carrying turntable, and a phonograph pick-up arm unit on the single frame means adjustable vertically to at least two playing positions spaced apart vertically, a removable pedestal positioned on the record 35 means on the turntable, said pedestal including a bottom member removably resting upon said record means, and a top member spaced above said bottom member adapted to have record 40 means resting thereon to be played by said pick-up arm unit at the upper one of the two playing positions, post means secured to said bottom member and said top member and extending intermediate the same to space them apart, and clamp means on said post means for clamping 45 record means of various sizes and thicknesses on said top member including anchor means within said post means, a transverse clamp member pivotally connected to and retained on said anchor means, and yielding means within the post engaging said anchor means to urge said anchor means downwardly and in turn exert a downward pull on said clamp member.

DONALD H. MITCHELL. 60
